HENRY ISTELLI, OF CENTRAL SAN GERMAN, ORIENTE, CUBA.

PROCESS AND APPARATUS FOR TREATING BAGASSE.

Application filed December 24, 1925. Serial No. 77,550.

This invention relates to a process and apparatus for treating sugar bearing materials and particularly for treating sugar cane.

The purpose of the invention is to increase 5 the extraction of sugar beyond that attainable at present with the modern commercial devices, by supplementally continuing the extraction in a particular manner beyond the usual treatment, and after the practical 10 possibilities of roller mills or other means are exhausted. This may be effected by simple means, involving practically no radical change of existing installations, without increase of labor, requiring no increase of 15 maceration water, and with the consumption of only a moderate amount of power.

In the application of the present invention to the extraction of sugar from sugar cane the bagasse is treated in an apparatus which 20 is placed anywhere in the path of the bagasse in the process of extracting sugar therefrom and in subsequent treatment. While passing through the apparatus, the bagasse is macerated, thoroughly agitated and commingled 25 with the maceration liquid; then the liquid is extracted and the bagasse is finally dried. The operation of extraction can be intensified to the extent of partially drying the bagasse or, in other words, subjecting it to 30 over-extraction. This treatment besides being simply maceration, commingling, extraction and drying, consists in a constant repetition of these steps, and these steps may be repeated any number of times. Finally, 35 after the last extraction step, the bagasse is subjected to a more intense and prolonged complete drying.

As is well known, in every cane sugar factory, the cane is macerated or sprayed 40 with water and the juice separated by subjecting the cane to very high pressure between the rolls of usually five or six roller mills. Each mill produces only one extraction, and there is no special provision for 45 commingling the resultant bagasse with the water with the consequence that considerable amount of bagasse does not come at all in contact with water. In a single relatively small unit of the apparatus to be described 50 we may have not only five or six extractions, but as many as twenty or more. The commingling of water and bagasse is performed under continuous stirring, splitting up and transposition of bagasse and is an important 55 feature of this invention, because it increases

the efficiency of maceration by driving the air out of the pores of the bagasse and bringing it into closer contact with the extracting liquid.

Another purpose of the present invention 60 is to provide for drying the final bagasse before passing it to the furnaces with the view of reducing or completely eliminating the necessity of extra fuel. It is well known that in the best operated cane sugar mills the 65 final bagasse emerging from the last roller mill contains around 50 to 48% moisture and that a considerable amount of extra fuel, usually wood or fuel oil, has to be burned in excess of bagasse to cover the total heat requirements. Further, although it is known 70 that the heat value of bagasse increases at a high rate with decrease of the moisture content, it is not generally appreciated that a further decrease of 10% to 15% would provide all the necessary heat and thus make 75 the cane sugar factory independent of extra fuel, and apparently for this reason no special device aiming at this result is to be found in modern sugar mills.

In my apparatus the drying, performed 80 simply as a continuation of the extraction process, is effected efficiently and economically. By not supplying the apparatus with water it can be adapted, especially in the 85 form shown in Fig. 5 (to be described later), alone to drying of the bagasse.

A still further purpose of the present invention is the replacing of one or two of the 90 last roller mills of any standard cane crushing and grinding installation by the apparatus to be described. It is a well known fact that the efficiency of the 4th, 5th and 6th mill in every cane sugar factory is very low, and besides, owing to the low speed of the 95 rolls and high hydraulic pressure, the construction has to be very bulky and expensive.

The apparatus to be described is a high speed machine occupying just a fraction of the space required for a roller mill including its gearing and engine, and is designed to be easily installed in place of a roller mill and to be connected to the remaining mills in an exceedingly simple manner.

The details of construction and operation 105 of this invention will be more fully explained with reference to the accompanying illustrations in which the apparatus is shown more or less diagrammatically.

Fig. 1 represents a vertical longitudinal 110

sectional view of the apparatus, showing alternate stationary, solid elements and rotatable perforated elements;

Fig. 2 represents a sectional view through a stationary cylinder and shows the casing around a rotary cylinder. This view also shows the means for mounting the paddles, and the diaphragm which is placed between the stationary and rotary cylinders;

Fig. 3 shows the end cover of the apparatus with the entrances for air and the material to be treated;

Fig. 4 is a detail sectional view showing the means for mounting a rotary cylinder;

Fig. 5 represents a vertical longitudinal section of a modified form of apparatus;

Fig. 6 and Fig. 7 show details of a device for introducing water into a rotary cylinder;

Fig. 8 illustrates the movement during the spreading of material with low blades;

Fig. 9 shows the path that the material takes with respect to the paddles when passing through the apparatus;

Figs. 10, 11 and 12 are detail views of the paddles used in the apparatus shown in Fig. 1; and

Figs. 13, 14, and 15 are detail views of the paddles used in the apparatus shown in Fig. 5.

Like parts throughout the several figures are identified by the same reference characters.

Referring to Fig. 1, the apparatus consists essentially of a number of stationary cylindrical shells 12, having imperforated side walls, and a number of rotary cylindrical shells 13, having perforated side walls placed alternately and end to end. The first cylinder 12 is a solid, wall stationary cylinder and is provided with a cover 14 having a large opening 15 for the entrance of the material to be treated, for example, bagasse, and openings 16 for the passage of air. The end section 12' is an inverted U-shaped section, solid and stationary and is provided with a cover 17 having openings 18 for the entrance of air. A shaft 19 rests on bearings 20 and 21 on the covers 14 and 17, respectively. The shaft may be rotated by any suitable means, as represented in the drawing by a motor 22.

The apparatus in Fig. 1 is shown installed after the last roller mill of a standard crushing and grinding installation, above the bagasse carrier 23, and on beams 24 laid across the bagasse carrier canal. The bagasse is scraped off the roller A by means of scraper 25 and slides down a chute 26, the upper end of which rests on the bagasse chute 27 of the roller mill and under the scraper 25. The lower end of the chute 26 rests on a casting 28 which is permanently bolted to the cover 14 and serves to direct the bagasse through the opening 15 into the first cylinder.

The stationary solid wall cylinders 12 are provided with openings 29 for water pipes 30 (see Fig. 2) through which maceration water enters at moderate pressure and forces the revolving bagasse toward the center of the cylinders, thus contributing toward efficient commingling. The first cylinder has a less number of openings for water than the succeeding stationary cylinders, since the main bulk of maceration water is supplied by a pipe 31 to the bagasse in the chute 26 in order to increase the mass and the speed of the falling bagasse and thereby project it into the cylinder above the paddles 32 which will be described later.

The cylinders 12 are also provided with partitions or incomplete diaphragms 33 of a crescent shape, as shown in Fig. 2. The purpose of these diaphragms is to permit the accumulation of liquid in the lower part of the stationary cylinders and also to retard, to a certain degree, the axial movement of the bagasse.

The rotary perforated wall cylinders 13 are provided with annular rings 34 at both ends. These rings slide in bearings 35, shown in detail in Fig. 4. The rotary cylinders are separated from the stationary cylinders by a light packing 36 which does not present much resistance to rotation. One form of bearing for the cylinders has been shown, but any form may be employed which will permit the rotation of the cylinders.

The cylinders 13 are caused to rotate by the friction produced by the rotating bagasse which is pushed around by the paddles 32 and 37. If the paddles rotate at approximately 1000 R. P. M., the cylinders make about 100 R. P. M. The rotation of these cylinders bears a certain relation to the axial displacement of the bagasse produced by the paddles which, like short pieces of a ribbon conveyor, are slightly inclined to the axis, as shown in Fig. 9. If the cylinders rotate at the same speed as the paddles, no axial displacement can take place, and if these cylinders are at a standstill, the axial displacement will be at its maximum. Consequently, the bagasse will move at a higher rate of speed in the stationary cylinders, or, in other words, remain for a shorter length of time in the stationary cylinders than in the rotating ones. By varying the speed of the paddles, the bagasse can be subjected for a longer or shorter time to the extraction step or the drying step.

Every extraction can thus be intensified and a partial elimination of moisture from the bagasse can be accomplished in each stage of the process. A moderate amount of this over-extraction or drying in each stage is beneficial, because a greater number of capillary cells in the bagasse is emptied and upon further maceration, these become re-filled, or, in other words, a greater number of

cells is washed out in every stage, which conduces to a more complete and efficient operation of the apparatus. Obviously, the over-extraction or drying can be accomplished directly by making the cylinders of efficient length and giving the paddles the proper inclination. In this manner, the time for the treatment may be fixed, and the bagasse can be made to go through the desired number of helical turns in each cylinder. A certain degree of control may be exercised either by an independent change of speed of the rotary cylinders, or by varying the speed of the motor 22, or by both, to take care of the quantity and the quality of the bagasse, as well as the variations in the operation of the mills.

Scrapers of one form or another may be used to clean the outside surface of the perforated rotary cylinders and to serve the purpose of a brake to keep the speed of the rotating cylinders and the axial displacement of the bagasse within certain desired limits. To further clean the perforations at intervals, a steam pipe 38, having nozzles 39, may be provided for each rotary cylinder. The perforated cylinders being rotary, a uniform discharge of liquid is obtained and the centrifugal force also helps to keep them clean.

While it is intended to produce the rotation of the perforated cylinders by the friction of the revolving paddles, this arrangement is not an essential feature of the invention. The rotation may be produced independently of the paddles by applying a driving means directly to the cylinders by means of pulleys, gears, sprockets or otherwise.

Each rotating cylinder is provided with an inverted U-shaped casing 40, an end view of which is shown in Figs. 2 and 3. These casings collect the separated liquid that is projected through the perforations of the cylinders. The liquid flows to the bottom, out through pipe 41 and into tank 42. From this tank the liquid is pumped to the roller mills of the factory for maceration purposes. The liquid may also be pumped to the pipe 31 for macerating the bagasse, emerging from the last roller mill, or it may be used in any of the stationary cylinders by pumping it through pipes 30. By certain pipe connections, the distribution of the liquid may be made in any desirable manner. It is desirable to first use all the water going to the roller mills, in the present apparatus. The bagasse is thus treated with fresh water and the cane passing through the grinding mills is treated with a slightly sucrose liquid.

The inverted U-shaped casing 40' around the last rotating cylinder catches the dust and minute particles of bagasse that may be projected out by this cylinder. This cas-

ing has no bottom and the dust falls directly on the bagasse carrier 23. The inverted U-shaped end section 12' has an opening 28' for the discharge of the main bulk of the bagasse onto the carrier 23.

The paddles 32 are mounted, as shown in Fig. 2. A hub 43 rests on the shaft 19 and radiating from the hub are spokes 44 supporting a ring 45. Rods 46, shown in Fig. 1, pass through the ring and attached to these rods are pieces 47, which hold the paddles 32. Each paddle is rotatable at rod 46, as shown at 47', so as to prevent jamming and the formation of a bagasse wedge between the paddles and the cylinders. It is preferred to have the paddles weighted at their tips, so that when the shaft is in motion, they will tend to be restored to the radial position.

All the paddles are so placed that there is a space of about an eighth of an inch between the inner surface of the cylinders and the outer edges of the paddles. The paddles near the diaphragms 33 or the end 14 are tapered inwardly, as shown in Fig. 1. This is done to avoid the accumulation of fibre between the diaphragm and the adjoining edge of the paddle and also to prevent the jamming and cutting of the fibre by the edge of the blade and the edge of the diaphragm.

Although Fig. 1 shows two rows of paddles mounted on the rings 45, it is preferred to use short paddles in three or more rows and to stagger them to obtain a greater number of transpositions of the bagasse, as shown in Fig. 5. A plan view of the paddles is shown in Fig. 9, in their lowest position in the cylinders, the arrow B indicating the direction of movement of the paddles and the arrow C, the axial displacement of the bagasse. It will be seen that the path of the bagasse will be substantially helical. Every time the bagasse leaves a paddle, its speed and direction changes until it is caught by another paddle. In the upper parts of the cylinders, the bagasse released by a paddle will fall and scatter on the paddles below it which thus produces a continuous splitting of the bagasse layer and contributes to efficient commingling as well as extraction and drying.

It is advantageous to have a large number of paddles mounted on each ring, especially in the perforated cylinders, to obtain the most uniform distribution of bagasse possible over the cylinder surface. The extraction and drying will obviously be more efficient if the layer of bagasse is thin. A thin layer of bagasse may require cylinders with a large diameter or the use of two apparatus units in parallel.

In the operation of the apparatus, the chute 26 is put into place, as shown in Fig. 1, and the bagasse coming from the roller

mill slides into the first cylinder 12. If the apparatus is not to be used, the chute 26 may be promptly removed and the bagasse may be made to descend the chute 27 to the carrier 23, thus avoiding any delay at the mill end of the factory.

The bagasse passing down the chute 26 is sprayed by water falling from the pipe 31. The lower end of the casting 28 is higher than the paddles 32 and the ring 45, so that the water and the bagasse issue horizontally over the pieces 47 and are then caught by the paddles and rotated. Owing to the curvature of the paddles, the impregnated bagasse and water tend to take a helical path and are continuously pushed toward and into the next adjacent cylinder 13, which is perforated and rotary where an intense separation of liquid and fibre takes place. The liquid passes into tank 42 from which it is pumped to the mills and the bagasse is pushed into the next cylinder 12 which is imperforated and stationary where it is again subjected to a maceration and commingling treatment. This process is repeated until the bagasse gets into the last rotating cylinder where the separation process is continued and a prolonged drying takes place. To insure proper drying of the bagasse, a fan 48 is placed in the end section 12' to send a current of air through practically the whole length of the apparatus and in an opposite direction to the motion of the bagasse. The bagasse is finally pushed into the end section 12' where it falls through opening 28' onto the carrier 23.

Depending on the origin and the quality of the cane, a certain amount of bagasse powder may be formed in the apparatus. In order to prevent any loss of the dried bagasse which serves as fuel, a very thin layer of molasses drops may be spread over the bagasse while passing along on the carrier 23. Drip pipes 49, having very small orifices may be used.

A modification of the above apparatus is shown in Fig. 5. While the number of macerations and extractions in the apparatus, shown in Fig. 1, is limited by the length of the apparatus, the construction shown in Fig. 5 allows for a much greater number of these operations with a smaller sized unit.

The apparatus, shown in Fig. 5, consists of a stationary solid wall cylinder 12, as in Fig. 1, and a rotary perforated wall cylinder 50, similar to cylinders 13, but considerably longer.

A modification of the means for introducing maceration water is also shown in Fig. 5. A perforated pipe 51 is shown mounted on the hubs 43. The open ends of said pipe 51 (see Figs. 6 and 7) pass through a disc 52 which is rigidly mounted on the shaft 19 and forms one end of a chamber 54. The cast-

ings 55 and 56 make up the cylindrical wall of said chamber and a disc 53, similar to disc 52, closes the other end of said chamber. The castings are held together by bolts 57 and 58. The casting 56 is adjustably fastened to the end section 12' by means of a rod 59 and held in rigid position by means of a set screw 60. A pipe 61 passes through the casting 56 and its end opens into the chamber 54. The discs 52 and 53 rotate with the shaft 19 along with the perforated pipe 51, and they slide in the packing rings 62 and 63. The chamber 54 is watertight and the water coming from pipe 61 fills the chamber 54, passes through the pipe 51 and is sprayed on the material in cylinder 50. Any number of maceration places may be established in the cylinder 50 by the proper distributions of the perforations in the pipe 51.

To avoid the passage of the water through the perforations in the cylinder 50 without percolating through the bagasse, it is preferred to make the height of paddles 32 and 37 sufficiently small, so that, as shown in Fig. 8, they will push a certain portion of bagasse 64 at their own speed on their front side while the rest of bagasse is driven over them and gets behind the paddles.

Figs. 10 to 15 inclusive show the relative positions of the paddles. In Fig. 10 portions of two adjacent wheels are shown bearing paddles A, B and A', B', respectively. Looking at these wheels from the right of Fig. 10, the view shown in Fig. 11 is obtained. Fig. 12 represents a plan view of the paddles that may be obtained when looking directly at the edge of the paddles and at the rims of the wheels shown in Fig. 10. In Fig. 13 a portion of a wheel is shown carrying more than one paddle on each rod 46. One rod will support four paddles C, for instance, and the next rod around the wheel will have three paddles D and so on alternately, the paddles D being staggered with respect to the paddles C. Looking at the wheel from the right of Fig. 13, the view shown in Fig. 14 is obtained. Fig. 15 represents a plan view of the paddles when looking directly at the rim of the wheel shown in Fig. 13. In both Figs. 1 and 5 the paddles will be longitudinally staggered with respect to each other.

Since the paddles are inclined with respect to the axis of the apparatus, their outer scraping edges must be slightly curved (as shown in Figs. 10 and 13) in order that they properly conform to the curvature of the inner surface of the cylinders and be uniformly spaced therefrom.

The shaft in the apparatus shown in Figs. 1 and 5 must be given a clockwise rotation to push the material from the receiving end of the apparatus to the discharge end.

It is seen that the process to which the

stug bearing material is subjected is a continuous one and consists of a successive repetition of the steps of macerating the bagasse, agitating and commingling the bagasse with an extracting fluid, separating the sugar solution produced from the material and drying the material.

The installation of the apparatus described does not require any increase in the amount of maceration water used in the modern factory because after passing through the apparatus it is sprayed on the mills.

What I claim is:—

1. In the process of treating bagasse, which process consists in agitating and commingling the bagasse with extracting fluid, simultaneously spraying the bagasse with the fluid, and separating from the bagasse the sugar solution produced.

2. The process of treating bagasse, which process comprises successively repeating the steps of macerating the bagasse, separating the maceration fluid from the bagasse, and subjecting the bagasse to a drying treatment with a current of air.

3. The process of treating bagasse, which process consists in allowing the bagasse to fall in a scattered condition into a body of extracting liquid, spraying the falling, scattered bagasse with extracting liquid, and separating the bagasse from the sugar solution produced.

4. The process of treating bagasse, which process consists in allowing the bagasse to fall in a scattered condition into a body of extracting liquid, spraying the falling, scattered bagasse with extracting liquid, and repeating the foregoing steps.

5. The process of treating bagasse, which process comprises macerating the bagasse, agitating and commingling the bagasse with extracting fluid, separating the sugar solution produced from the bagasse, and then agitating and commingling the bagasse with the sugar solution obtained in the first separation step, and separating the liquid from the fibrous matter.

6. The process of treating bagasse, which process comprises successively repeating the steps of macerating the bagasse, agitating and commingling the bagasse with the extracting fluid, separating the sugar solution produced from the bagasse, and subjecting the bagasse to a drying treatment with a current of air.

7. The process of treating bagasse, which process consists in allowing the bagasse to fall in a scattered condition into a body of extracting liquid, spraying the falling, scattered bagasse with extracting liquid, separating the bagasse from the sugar solution produced, then allowing the bagasse to fall in a scattered condition and simultaneously blowing air through the falling, scattered bagasse to thereby dry the same.

8. The process of treating bagasse, which process comprises successively repeating the steps of macerating the bagasse, separating the maceration fluid from the bagasse, and subjecting the bagasse to a drying treatment with a current of air, the said process being continuous.

9. The process of treating bagasse, which process comprises successively repeating the steps of macerating the bagasse, agitating and commingling the bagasse with the extracting fluid, separating the sugar solution produced from the bagasse, and subjecting the bagasse to a drying treatment with a current of air, the said process being continuous.

10. The process of treating bagasse, which process comprises successively repeating the steps of agitating and commingling the bagasse with extracting fluid, separating the sugar solution obtained from the bagasse, and subjecting the bagasse to a drying treatment with a current of air.

11. The process described in claim 4 in which the bagasse, after the last extraction step, is subjected to a prolonged drying treatment.

12. The process described in claim 6 in which the bagasse, after the last extraction step, is subjected to a prolonged drying treatment.

13. The process of treating bagasse, which process consists in passing the bagasse through a maceration operation in small quantities, while adding an extracting fluid, agitating and commingling the bagasse with the fluid, removing the macerated bagasse from the sphere of operations, replacing the macerated bagasse with more bagasse, separating the solution of sugar from the macerated bagasse, while maintaining all the bagasse in continuous agitation.

14. The process of extracting sugar from bagasse, which process comprises successively repeating the steps of macerating the bagasse and separating the sugar solution produced from the bagasse, while maintaining the bagasse in continuous agitation.

15. The process of treating bagasse, which process consists in agitating the bagasse by periodically subjecting it to an alternate impelling action and release, and simultaneously spraying the bagasse with extracting fluid.

16. The process of treating bagasse, which process consists in agitating the bagasse by periodically subjecting it to an alternate impelling action and release, and simultaneously drying the bagasse with a current of air.

17. An apparatus for treating bagasse, consisting of a chamber, a power driven member mounted in said chamber, a plurality of supports mounted on said member and rotatable therewith, a plurality of short ribbon-like paddles carried by each support, the

said paddles being longitudinally staggered with respect to each other and inclined with respect to the power driven member.

18. An apparatus for treating bagasse, the said apparatus having a plurality of cylindrical shells placed end to end, at least one of said cylindrical shells being stationary and having its side wall imperforated, and the cylindrical shell next adjacent to said stationary shell being rotary and having its side wall perforated.

19. An apparatus for treating bagasse, the said apparatus having a plurality of cylinders placed end to end, a stationary solid wall cylinder and next adjacent to it a rotary perforated wall cylinder, and means for pushing the bagasse through the cylinders.

20. An apparatus for treating bagasse, the said apparatus having a plurality of cylindrical shells placed end to end, at least one of said cylindrical shells being stationary and having its side wall imperforated, and the cylindrical shell next adjacent to said stationary shell being rotary and having its side wall perforated, and means for pushing the bagasse in a helical path through said cylindrical shells.

21. An apparatus for treating bagasse, the said apparatus having a plurality of cylindrical shells placed end to end, at least one of said cylindrical shells being stationary and having its side wall imperforated, and the cylindrical shell next adjacent to said stationary shell being rotary and having its side wall perforated, means for macerating the bagasse, and means for collecting the maceration liquid extracted from the bagasse.

22. A multiple sugar extractor and bagasse drier comprising a machine unit having inlet and outlet means for the bagasse, means for macerating the bagasse, means for commingling the bagasse with maceration liquid, means for extracting the sugar solution formed from the bagasse, and means for drying the bagasse.

23. A multiple sugar extractor and bagasse drier comprising a machine unit having inlet and outlet means for the bagasse, means for macerating the bagasse, means for commingling the bagasse with maceration liquid, means for extracting the sugar solution formed, and means for drying the bagasse.

24. A multiple sugar extractor and bagasse drier comprising a machine unit having inlet and outlet means for the bagasse, means for supplying a liquid to the bagasse, paddles for commingling the bagasse with the liquid and for pushing the bagasse from the inlet to the outlet of the machine, straining means over which the bagasse passes to separate the sugar solution produced from

the bagasse, and means for passing a current of air over the bagasse to dry it.

25. A multiple sugar extractor and bagasse drier comprising a machine unit made up of a plurality of cylindrical shells placed end to end and in alignment with each other, the first of said cylindrical shells being stationary and having its side wall imperforated and having means for passing bagasse into it, the second of said cylindrical shells being rotary, and having its side wall perforated, means for passing the bagasse from the stationary cylindrical shell into the rotary cylindrical shell; means for macerating the bagasse, means for collecting the sugar solution separated from the bagasse, and means for drying the bagasse while passing through the cylindrical shells.

26. A multiple sugar extractor and bagasse drier comprising a machine unit, consisting of a series of alternately arranged stationary solid wall cylinders and rotary perforated wall cylinders joined end to end and in alignment with each other, means for passing the bagasse into the first cylinder, means for macerating the bagasse in the stationary solid wall cylinders, means for commingling the bagasse with the extracting liquid and for passing the bagasse through the cylinders, means for collecting the liquid passing out of the perforated wall cylinders, and means for drying the bagasse.

27. The combination of a bagasse treating apparatus with a roller mill of a standard cane crushing and grinding installation, means for passing the bagasse from the mill to a point away from the bagasse treating apparatus, and means adapted, when in its operative position, to form a closure for the first named means and to pass the material from the mill to the bagasse treating apparatus.

28. An apparatus for treating bagasse, consisting of a chamber, a rotatable member mounted in said chamber, a plurality of supports mounted on said member and rotatable therewith, short ribbon-like paddles carried by said support, the said chamber having a wall in line with said power driven member, the said wall conforming with the path of travel of the tips of the blades whereby each of said paddles impart to the bagasse a helical motion.

29. A process for treating bagasse, the said process consisting in scattering the bagasse particles into an open condition with respect to each other, and spraying the bagasse with extracting fluid while in said open condition.

30. A process for treating bagasse, the said process consisting in lifting the bagasse and scattering the bagasse particles in open

condition with respect to each other and injecting an extracting fluid into the bagasse while in said open condition.

31. An apparatus for treating bagasse, including rotatable elements adapted to revolve rapidly for scattering the bagasse particles into open condition with respect to each other, and spraying elements so positioned as to convey a spray of extracting fluid to the particles of bagasse while in said open condition.

32. An apparatus for treating bagasse, including means for scattering the bagasse particles into open condition with respect to each other, and means for spraying an extracting fluid across the path taken by the scattering bagasse whereby it is treated with said fluid while in said open condition and while it is under the influence of the said scattering means.

33. An apparatus for treating bagasse, including a casing having inlet and discharge

openings for bagasse, a scattering mechanism located adjacent said inlet opening and including rotary elements adapted to 25 propel incoming bagasse lengthwise of said casing and to scatter the particles of bagasse into open condition with respect to each other, and means for projecting an extracting fluid across the path of the scattered 30 bagasse particles.

34. An apparatus for treating bagasse, the said apparatus including a casing having inlet and discharge openings for bagasse, a scattering mechanism located adjacent said 35 inlet opening and adapted to propel the incoming bagasse in scattered condition, means for feeding bagasse to said scattering mechanism, and means for projecting an extracting fluid across the path of the 40 scattered bagasse particles.

In testimony whereof I affix my signature.

HENRY ISTELLI.
